COUPLING ARRANGEMENT

Application filed September 21, 1927. Serial No. 221,091.

This invention relates to coupling arrangements, and more particularly to such arrangements used to change impedance and phase relation.

5 It is frequently desired to couple circuits together with a change in impedance, as, for example, when matching the impedance at the junctions in branched transmission lines. With very high frequencies it is not feasible 10 to obtain the desired impedance changes by the use of simple transformer circuits because insulation is so difficult that reasonably close coupling between the primary and secondary is impossible. To use a parallel 15 resonant circuit and couple the output at variable tapping points on the inductance of the circuit makes it impossible to obtain zero phase shift, and is relatively inefficient for it involves high losses owing to the 20 circulating current in the resonant circuit.

It has been proposed to couple a series circuit of inductive and capacitive reactances across one of the external circuits, and to couple the other external circuit across either the inductive or capacitive reactance. This arrangement is satisfactory but has the disadvantage that there is involved an inherent phase shift the direction of which is determined by that reactance across which the second external 25 circuit is coupled, and the magnitude of which is fixed for any given impedance ratio. It is an object of my invention to provide a coupling arrangement which is efficient even at very high frequencies and 30 which permits optional impedance change and phase shift.

To do this I change the impedance successively by means of cascade connected coupling circuits the impedance ratios of which 40 are such that their product equals the desired ratio, and the phase shifts in which are such that their algebraic sum equals the desired phase shift. In the special case of zero phase shift the arrangement comprises two 45 of the series circuits such as have been described, the impedance ratios of which are equal to the square root of the desired overall impedance ratio, and the phase shifts in which are equal but opposite in direction, a 50 result which is obtained by coupling the

second coupling circuit to the first coupling circuit across either the inductive or capacitive reactance, and coupling the second external circuit to the second coupling circuit across the capacitive or inductive reactance, 55 respectively.

The invention is described more in detail in the following specification which is accompanied by a drawing in which

Figure 1 and Figure 2 represent known 60 coupling circuits;

Figure 3 is a combination of known circuits embodying my invention;

Figure 4 is a graph which is useful when selecting the circuit constants; and 65

Figure 5 symbolically indicates an application of my invention.

Referring to Figure 1 there is shown a series circuit comprising the inductances 2 and the capacitance 4, which are connected 70 by means of the terminals 6 to an external circuit. The terminals 8, connected to the condenser 4, lead to a second external circuit. The reactance values are so chosen that when the parallel circuit consisting of the resistance of the output circuit and the capacitance 4 is transposed to an equivalent series circuit of capacitance and resistance the inductance 2 resonates with the fictitious series capacitance, and the fictitious series resistance 75 is equal to the desired line impedance. In the direction from the terminals 6 to the terminals 8 the impedance is stepped up, but by connecting the circuit in the opposite direction the impedance may be stepped down. 80

Figure 2 is similar to Figure 1 except that the terminals 18 have been connected to the inductive reactance 12 instead of to the capacitive reactance 14. In this case the parallel circuit consisting of the resistance of 90 the second external circuit, that is, the circuit across the terminals 18, and the inductance 12, may be transposed into an equivalent series circuit of inductance and resistance, and the capacitance 14 resonates with 95 the fictitious inductance, while the fictitious resistance is the desired line impedance for the external circuit connected to the terminals 16.

In Figure 4 the curve 20 shows the degrees 100

of phase shift between the first and second external circuits as a function of the impedance ratio. It is clear that when employing circuits such as have been shown in Figures 5 1 and 2 the curve 20 is symmetrical, the phase shifts for either the capacitive or inductive couplings being equal for a given impedance ratio, but opposite in direction.

Advertising now to Figure 3 it will be seen
10 that in accordance with my invention the coupling arrangement comprises a combination of the circuits shown in Figures 1 and 2. In this manner if the impedance ratios are equal, the resultant phase shift is zero. Thus, in
15 the special case where zero phase shift is desired the two circuits are so designed that the impedance ratio of each is equal to the square root of the desired ratio, so that the overall ratio is that desired, and meanwhile
20 the equal but opposite phase shifts in the two parts of the coupling arrangement neutralize one another so that the resultant phase shift is zero.

In the more general case the requirement for a desired impedance ratio accompanied by a desired phase shift is met by combining circuits the product of the impedance ratios of which is that desired while the algebraic sum of the phase shifts in which is that desired, which involves factoring the desired product into those factors, from among the many possible groups of factors, which give the correct phase shift. This selection may be readily accomplished by the use of a chart such as has been shown in Figure 4, the curves 22, 24, 26 and 28 of which are plotted to the same scale of ordinates and abscissæ as the curve 20, but which represent overall impedance ratio as a function of overall phase shift when using the combined circuit shown in Figure 3. The curve 22 is obtained by assuming that the impedance ratio of one of the circuits is 0.2 and taking various values from zero to one for the other circuit. The curve 24 is obtained by assuming that the impedance ratio of one of the circuits is 0.4 and taking various values for the other circuit. Similarly curves 26 and 28 are obtained by assuming impedance ratios of 0.6 and 0.8 respectively for one of the circuits.

The chart may be used as follows. A point representing the desired impedance ratio and phase shift is located on the chart, such as the point 30, located at an impedance ratio of 0.4 and a phase shift of 30 degrees lagging. The point 30 is followed out on a line 32, approximated from the nearest adjacent curve, until it intersects the curve 20, which indicates the phase shift and the impedance ratio for one of the coupling circuits to be 48° and 0.45. The impedance ratio of the other of the circuits may be obtained by dividing the desired ratio by the ratio found for the first circuit, which comes out 0.89, or by subtracting the desired phase shift from the phase shift in

the first circuit to obtain the phase shift in the second circuit, namely, 18° leading, and locating the impedance ratio for that phase shift on the curve 20, giving slightly less than 0.9, which is as it should be.

So, in Figure 4, the lines 34 and 36 represent the impedance ratio and phase shift for one of the circuits, while the lines 38 and 40 represent the impedance ratio and phase shift for the other of the circuits. It will be seen that the phase shifts differ by 30 degrees, and that the product of the impedance ratios equals 0.4, as was desired.

The chart as drawn serves only for values of ratio and shift which lie within the boundaries of the curve 20, for it has been assumed that the circuits have phase shifts of opposite sense and impedance ratios of like sense, which is the more usual case. It is clear, however, that the chart may be extended to include more general cases by continuing the curves 22, 24, 26 and 28, which is done by taking impedance ratios for the second circuit which are greater than unity. One such curve is shown in Figure 4, curve 22. To obtain ratios greater than unity one of the coupling circuits in Figure 3 is reversed.

An application of my invention is indicated in Figure 5, in which there are broadside 95 antennæ 102 and 104, with energized reflectors 106 and 108, fed by transmission lines 110 and 112, which in turn are fed by a transmission line 114. Such antennæ are described in a copending application of Nils E. Lindenblad, Serial No. 229,407, filed October 28, 1927. If the transmission lines 110 and 112 are similar to the transmission line 114 their combined impedance is half of that of line 114, and therefore impedances must be matched at the junction point 116. At this junction a phase shift is not injurious, and therefore the older type of coupling arrangements may be employed. But at the points 118 and 120, where the line impedances also 110 must be matched, the relative phase of the energies supplied to the antennæ 102 and 106 is of great importance, for their phase displacement should equal the natural phase displacement of the wave in space at points spaced at the distance between the antenna 102 and the reflector 106. To meet this requirement my coupling arrangement may be applied at the points 118 and 120, and similarly at the points 122 and 124 for the other antenna. 115 120

I claim:

1. The method of obtaining a desired impedance ratio and a desired phase shift which includes changing the impedance successively by ratios the product of which equals the desired ratio, and accompanying the impedance changes with phase shifts the algebraic sum of which equals the desired phase shift. 125
2. The method of obtaining a desired im- 130

pedance ratio with no phase shift which includes changing the impedance by a ratio which is the square root of the desired ratio accompanied by a phase shift in one direction, and again changing the impedance by the square root of the desired ratio accompanied by an equal phase shift in the opposite direction.

3. A coupling arrangement for obtaining 10 a desired impedance ratio and a desired phase shift comprising a plurality of cascade connected impedance changing devices the product of the ratios of which equals the desired ratio and the algebraic sum of the phase 15 shifts in which equals the desired phase shift.

4. A coupling arrangement for obtaining 20 a desired impedance ratio with no phase shift comprising a plurality of cascade connected impedance changing devices having impedance ratios the product of which equals the ratio desired, and the algebraic sum of the 25 phase shifts in which equals zero.

5. A coupling arrangement for obtaining a 25 desired impedance ratio with no phase shift comprising two impedance changing devices having equal impedance ratios, and equal but opposite phase shifts, connected in cascade.

6. An arrangement for changing impedance and phase by desired amounts comprising 30 an external circuit, a coupling circuit connected thereto and having inductive and capacitive reactances in series, a second coupling circuit having inductive and capacitive reactances in series coupled across a reactance 35 of one sign of the first coupling circuit, and a second external circuit coupled across a reactance of another sign of the second coupling circuit.

7. An arrangement for changing impedance 40 and phase by desired amounts comprising an external circuit, a coupling circuit connected thereto and having inductive and capacitive reactances in series, a second coupling circuit having inductive and capacitive 45 reactances in series coupled across a reactance of one sign of the first coupling circuit, and a second external circuit coupled across a reactance of another sign of the second coupling circuit, the coupling circuits having impedance 50 ratios the product of which equals the desired ratio, and phase shifts the algebraic sum of which equals the desired phase shift.

8. An arrangement for changing impedance and phase by desired amounts comprising 55 an external circuit, a coupling circuit connected thereto and having inductive and capacitive reactances in series, a second coupling circuit having inductive and capacitive reactances in series coupled across the inductive reactance 60 of the first coupling circuit, and a second external circuit coupled across a capacitive reactance of the second coupling circuit.

9. An arrangement for changing impedance 65 and phase by desired amounts comprising an external circuit, a coupling circuit

connected thereto and having inductive and capacitive reactances in series, a second coupling circuit having inductive and capacitive reactances in series coupled across the inductive reactance of the first coupling circuit, and a second external circuit coupled across the capacitive reactance of the second coupling circuit, the coupling circuits having impedance ratios the product of which equals the desired ratio, and phase shifts the algebraic 70 sum of which equals the desired phase shift.
